APPARATUS FOR STRETCHING AND DRYING SKINS, LEATHER, AND OTHER MATERIALS

Filed Feb. 8, 1923

Patented Mar. 15, 1927.

UNITED STATES PATENT OFFICE.

EWALD E. KORNITZ, OF MILWAUKEE, WISCONSIN, ASSIGNOR OF ONE-HALF TO CARL A. BECHSTEIN, OF MILWAUKEE, WISCONSIN.

APPARATUS FOR STRETCHING AND DRYING SKINS, LEATHER, AND OTHER MATERIALS.

Application filed February 8, 1923. Serial No. 617,800.

This invention relates to certain new and useful improvements in apparatus for stretching and drying skins, leather and other materials and is an improvement over the structure illustrated in Letters Patent No. 1,438,355, issued December 12, 1922, to Carl A. Bechstein and Ewald E. Kornitz, and refers more particularly to the construction of the frame and the means for protecting relative movement between the sections thereof.

It is a general object of this invention to simplify the means for procuring relative movement between the frame sections and which will insure uniform movement on the part of the frame sections.

It is another object of this invention to provide means for moving the main frame sections toward and away from each other and means independent thereof and operable upon actuation of the first mentioned means to procure corresponding movement of the other frame sections.

Another object of this invention resides in the provision of toggle means connecting the various frame sections for procuring relative movement therebetween whereby simplicity of design together with maximum strength is procured.

A further object of this invention resides in the provision of a supporting frame member having a pair of main parallel frames slidably mounted therein for movement toward and away from each other and a pair of auxiliary frame sections carried one by each main frame and adapted for longitudinal movement therein.

And a still further object of this invention resides in the provision of an improved manner of attaching a foraminous plate or cover to the frame sections in order to facilitate the ready attachment thereto of the material to be dried.

With the above and other objects in view which will appear as the description proceeds, my invention resides in the novel construction, combination and arrangement of parts substantially as hereinafter described and more particularly defined by the appended claims it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side elevational view of my improved expansible frame, a skin or other material being illustrated in dotted lines as attached thereto, parts of the foraminous covering of several of the sections being broken away in order to illustrate the details of construction;

Figure 2 is a sectional view taken transversely through Figure 1 on the plane of the line 2-2, and

Figure 3 is an enlarged fragmentary view, partly in section and partly in elevation, said view being taken through Figure 1 on the plane of the line 3-3.

Referring now more particularly to the accompanying drawing in which like numerals designate like parts throughout the several views, the numeral 5 designates a rectangular supporting frame constructed of tubing or other material and adapted to be portably suspended from an overhead track 6 by trolleys 7 to facilitate transportation of the apparatus to and from drying rooms or other places. The supporting frame has mounted therein for side-wise movement a pair of parallel main frame members 8, each consisting of the frame-work or side bars 9 of tubing or the like. The frames 8 have end brackets 9' carrying rollers 10 which track on the upper and lower bars 11 of the frame 5 to thus permit unrestricted movement of the frame members toward and away from each other and to maintain the same in a common plane.

Each frame member 8 has an intermediate division bar 12 dividing the same into an upper and lower section, the lower section thereof being covered with a foraminous or perforated covering 13 preferably in the form of sheet material provided with a plurality of openings 14. The covering is attached to the frame 8 by having its end secured to channel bars 15 which in turn straddle the side bars of the frame and are secured thereto by suitable fastenings 16. This construction places the surface to which

the material is attached on a higher plane scribed, comprising supporting means, a plurality of frame members, means for attaching work to the frame members, means connecting the frame members with the supporting means whereby they are permitted 70 movement toward and away from each other with their work engaging surfaces in a substantially common plane, and means connecting the frame members and operable to procure relative movement therebetween. 75

5 An auxiliary section 17 is longitudinally slidably mounted between the side bars of the upper half or section of each main frame by bearing members 18 carried by the auxiliary sections and slidably engaging the 10 main frame side bars. Each auxiliary section is provided with a covering 13 similar to that of the lower portion of the main frames.

15 In operation, the skin, leather or other material 19 to be stretched and dried is secured to the apparatus in substantially an even, taut condition by fastening members 20 having hooked ends adapted to be inserted in the apertures 14 and the main frames 20 and auxiliary sections then expanded to complete the stretching operation. It is essential that this relative movement between the parts or various frame sections be uniform, and, in the present embodiment, it is accomplished by a rod 21, the ends of which are threaded, as at 22, and passed through nuts 23 centrally secured in the upper and lower bars 11 of the frame 5, whereby rotation of the rod 22, by a crank (not shown) inserted 30 on its keyed end 24, will procure longitudinal movement thereof.

Longitudinal movement of rod 21 imparts a movement between the main frames toward or away from each other as pairs of toggle members or links 25 are pivotally secured, as at 26, to collars 27 freely rotatably secured on the shaft 21 by fixed collars 28 with their lower ends pivotally secured, as at 29, to brackets 30 carried by the inner 40 side bars of the frames 8.

With this construction it will be obvious that with the parts in the positions illustrated in Figure 1, a movement of rod 21 in the direction of the arrow 31 spreads the frames 8 and a movement of the rod in a reverse direction contracts the main frames. This movement of frames 8 is transmitted to the auxiliary sections 18 by pairs of toggles or links 32, secured in pairs by a common pivot 33 to a rod 34 and having their outer ends secured to the adjacent end bar of the adjacent auxiliary section 13 and to the end bar 12 of the adjacent section 8.

As illustrated in the drawings two pairs 55 of toggle links connect each auxiliary section with the adjacent bar 12 and they are so arranged that a movement apart of the frames 8 will spread the toggles and a reverse movement of the frames 8 contract the same. With this construction a movement apart of the sections 8 effects a corresponding uniform movement of the auxiliary sections.

What I claim as my invention is:

65 1. An apparatus of the character de-

scribed, comprising pairs of frame members, the frame members of each pair being mounted for movement toward and away from each other and each pair being 80 mounted for movement toward and away from each other, means operable to move the pairs of frame members toward and away from each other, and means independent of the first named means and operable upon 85 movement of the pairs of frame members toward or away from each other to impart a corresponding movement between the frame members of each pair.

3. An apparatus of the character de- 90 scribed, comprising two parallel frames, means connecting the frames for movement toward and away from each other and adapted to maintain the same in a common plane, an auxiliary section carried by each frame, means adapted to maintain each auxiliary section in a common plane with its adjacent frame and in a slidable relationship longitudinally toward and away from its frame, toggle means connecting the 100 frames and the auxiliary sections with their frames, and means for actuating the toggles to effect relative movement between the frames and auxiliary sections.

4. An apparatus of the character de- 105 scribed, comprising two parallel frames, means connecting the frames for movement toward and away from each other and adapted to maintain the same in a common plane, an auxiliary section carried by each 110 frame, means adapted to maintain each auxiliary section in a common plane with its adjacent frame and in a slidable relationship longitudinally toward and away from its frame, a rod slidably mounted between 115 the frames, toggles connected with the rod and the frames and adapted upon sliding movement of the rod to spread the frames, and means operable upon spreading movement of the frames to produce spreading of 120 the auxiliary sections.

5. An apparatus of the character described, comprising two parallel frames, means connecting the frames for movement toward and away from each other and adapted to maintain the same in a common plane, an auxiliary section carried by each frame, means adapted to maintain each auxiliary section in a common plane with its adjacent 125 frame and in a slidable relationship longi- 130

- tudinally toward and away from its frame, a rod slidably mounted between the frames, toggles connected with the rod and the frames and adapted upon sliding movement of the rod to spread the frames, a bar extending across the frames between them and the auxiliary sections, and pairs of toggles carried by the bar and connecting the auxiliary sections with their frames, whereby spreading of the frames by said rod and the toggles carried thereby effects a spreading of the auxiliary sections through the medium of the bar and the toggles carried thereby.
6. An apparatus of the character described, comprising a rectangular frame including end and side bars, a pair of parallel frames including side and end bars, means carried by the end bars of the parallel frames and slidably engaging the end bars of the rectangular frame to retain the parallel frames in a common plane and permit their movement toward and away from each other, a covering for adjacent ends of the parallel frames, an auxiliary section slidably mounted in the other end of each parallel frame and capable of movement toward and away from the covered end of its parallel frame, and means for procuring relative movement between the parallel frames and the auxiliary sections.
7. An apparatus of the character described, comprising a frame member including side bar members, channel members secured to the side bars with their surface projected beyond the frame member, and a perforated covering secured to the channel members and providing a covering for the frame member.
8. An apparatus of the character described, comprising a pair of frame members, means for attaching work to the frame members, means mounting the frame members for movement toward and away from each other with their work engaging surfaces in a substantially common plane, a rod mounted between the frame members and adapted to be longitudinally shifted, toggle links, means connecting the toggle links with the rod and the frame members, whereby shifting of the rod imparts movement to the frame members, and means for longitudinally shifting the rod.

In testimony whereof I affix my signature.

EWALD E. KORNITZ.
